UNITED STATES PATENT OFFICE.

HENRY BAUKNECHT, OF MIDLAND, MICHIGAN.

WINDOW-SCREEN.

1,229,400.

Specification of Letters Patent. Patented June 12, 1917.

Application filed November 13, 1916. Serial No. 131,029.

To all whom it may concern:

Be it known that I, HENRY BAUKNECHT, a citizen of the United States, residing at Midland, in the county of Midland, State of Michigan, have invented certain new and useful Improvements in Window-Screens, and I do hereby declare the following to be a full, clear, and exact description of the invention, such as will enable others skilled in the art to which it appertains to make and use the same.

This invention relates to window screens, and has particular reference to adjustable screens.

The object of this invention is to provide a window screen which is adjustable, but which only spreads one screen section across the window space. It is well known that most adjustable or expandable window screens are formed of relatively slidable sections of similar or identical construction, so that when the screen is mounted in a window frame, the sections overlap through a middle portion, so that the screen appears in doubled relation and the vertical bars or sides of the over-lapping sections also tend to obstruct the view. My invention avoids this objectionable feature by providing a screen consisting of slidable frame sections, but a single extensible expanse of screening. In carrying out the invention, one of the slidable frame sections is provided with a roller upon which the unexpanded portion of the screen is rolled, the screen being drawn upon the roller as the frame sections are brought together.

With the above objects in view and such other objects as may hereinafter appear, my invention will now be fully set forth and described, reference being had to the accompanying drawings.

In the drawings:

Figure 1 is an elevation of the screen,

Fig. 2 is an enlarged elevation of the framing at one side which forms an inclosure for the roller, certain parts being broken away and others sectioned for the sake of clearness,

Fig. 3 is a section on line 3-3 of Fig. 1, and

Fig. 4 is a detail view of a locking device used in connection with the invention.

Referring more particularly to the drawings 1 and 2 respectively indicate the end sections of the screen which are joined by the intermediate sections 3. Each of the sec-

tions, 1, 2 and 3 is formed of channeled material, and the end sections consist of the vertical channels 4 and the horizontal arms 5, the latter extending toward one another from the upper and lower ends of the vertical elements 4 and being received in the channeled members 3. The channeled members or sections 3 are provided along their free edges with the inturned walls 7 which form a contracted passage 8 along the open side of the channel sections. The vertical element 4 of the section 1 constitutes a casing for a spring roller 9 whose upper and lower ends are provided with journals 10 mounted in the bearing plates 11, secured within the opposite ends of the casing. The upper and lower ends of the roller 9 also carry the pinions 12 which are fixed upon the roller and extend through slots 13 formed in one side of the roller casing or element 4. The roller 9 carries a sheet or strip of screening 14, and is controlled after the manner of the usual spring curtain roller, so that the normal tendency of the roller is to wind up the screen 14 whose free end is fixed within the channeled element 4 of the sections 2. The portions of the pinions 12 which extend beyond the side of the casing 4 are engaged by the pawls or lugs 15 which are mounted upon the upper and lower ends of a bowed leaf spring 16 mounted upon the outer face of the casing 4. Said spring 16 is bowed along its middle portion, and where it contacts with the casing 4 at opposite ends of the bowed portion, passes through the guide wings 17, and is thereby held in position. Pressure upon the middle bowed portion of the spring 16 fulcrums the spring upon the loops 17 and causes the pawls 15 to rise out of engagement with the pinions 12, thereby releasing the spring roller. Thus, the spring 16 with its pawls 15 acts as the normal lock for the roller.

The upper and lower edges of the screen 14 extend into the channeled portions of the arms 5 and in the sections 3, so that it is fully extended, and completely closes the opening formed by the sections. It is obvious that the narrowest folded limit of the screen is determined by the length of the sections 3 and the corner plates 18 which are secured across the corners of the sections 1 and 2, and the edges of the screening 14 which do not come into position to be rolled upon the roller 9 are bound with suitable

binding strips 19, the latter assisting in filling the channeled portions of the sections, and stiffening the screening material so that it will not bulge out of the upper and lower 5 portions of the sections.

Extending from the corners of the sections 2 to the adjacent ends of the sections 3 are the locking devices 20. Each of the locking devices 20 consists of a pair of pivoted arms whose free ends are pivotally connected as above stated to the sections 2 and 3, and whose joined ends are provided with the overturned locking lugs 21 which bear upon the opposing arms when the latter are 10 extended. Stop devices 22 are provided on the marginal faces of the members 5 to determine the minimum limit of the contraction 15 of the screen.

In the use of my improved screen, the device is adjusted approximately to the width 20 of the window in which the screen is to be placed, the spring 16 being released from contact with the pinions 12 so that the screening 14 may be extended or contracted, 25 the sections 1, 2 and 3 sliding relatively upon one another until the desired adjustment has been secured. The screen is then set within the window frame, and the locking devices 20 spread into opened or extended relation 30 so as to throw the section 2 to the limit of its adjustment away from the sections 3, thereby closely fitting the screen into the window frame. Thus, the device is initially adjusted to the window width and then the 35 additional expansion allowed by the locking devices is utilized to secure the screen within the window frame.

From the foregoing, it is evident that I have provided an improved form of window

screen which obviates the doubled portions 40 of the usual folding screen, and which may, at the same time be adjusted to windows of any width within reasonable limits. The device can be built as an all metal screen in order to meet the present day demands and 45 can furthermore be built without too great a cost to the manufacturer.

What I claim as my invention is:—

1. A folding screen, comprising in combination, opposing end sections and intermediate sections which are relatively slidable, a roller carried by one of the end sections, a length of screening mounted on the roller and secured within the opposing section, serrated locking wheels carried by the roller 55 and extending beyond the sides of the sections, and a spring bar carried by the section and having its ends resiliently engaged in said wheels.

2. A folding screen, comprising in combination, opposing end sections and intermediate sections which are relatively slidable, a roller carried by one of the end sections, a length of screening mounted on the roller and secured within the opposing section, serrated locking wheels carried by the roller 65 and extending beyond the sides of the section, a spring bar carried by the section and having its ends resiliently engaged in said wheels, and locking devices for expanding 70 the parts into window engaging position.

In testimony whereof, I affix my signature, in the presence of two witnesses.

HENRY BAUKNECHT.
